UNITED STATES PATENT OFFICE.

RICHARD M. BURKE, OF UTICA, NEW YORK.

RAIL CONSTRUCTION.

SPECIFICATION forming part of Letters Patent No. 787,434, dated April 18, 1905.

Application filed July 22, 1904. Serial No. 217,715.

To all whom it may concern:

Be it known that I, RICHARD M. BURKE, a citizen of the United States, residing at Utica, Oneida county, State of New York, have invented certain new and useful Improvements in Rail Construction, of which the following is a specification, reference being had therein to the accompanying drawings.

My invention relates to an improved rail construction; and I declare that the following is a full, clear, concise, and exact description thereof sufficient to enable one skilled in the art to make and use the same, reference being had to the accompanying drawings, in which like letters and numerals refer to like parts throughout.

A characteristic of my invention is the employment of a wide rail-base, which because of the distribution of the weight thereon lessens the wear on the ties or the substructure of the rail-bed and which by the employment of a removable rail-tread permits ready replacing of that part which is most subject to wear. A further advantage is that the base of the rail is provided with grooves to engage the rim of the wheel in case of derailment, and thus lessens the risk of disaster. A further feature is that the base and the tread are so constructed that the latter might extend over the former, so as to break joint, the two being pierced for connecting means at regular and coincident intervals.

In the drawings, Figure 1 is a perspective view, and Fig. 2 is a sectional view, of my device.

Referring to the figures more in detail, A represents railroad-ties or any other suitable substructure to support the rail portions.

B represents a rail-base which is provided between its edges with a vertical flange or web C, projecting vertically above the base. This flange is formed with substantially parallel sides, although it is not essential that this should be so, it being permissible that the outer face should vary somewhat from the true parallel to the inner face. The base B is grooved out adjacent to one of the faces, here shown as the inner one, and rises from such groove b into a shoulder b'. On the opposite

side of the flange C the base extends outwardly and downwardly, as shown at c. On each side of the flange C the base is then formed into the grooves D and the ridges D', from which point the sides of the base extend downwardly and laterally to an edge suitable for attachment to the ties or substructure, as shown by the spikes d in this instance.

I form a rail-tread with a horizontal member E and a vertical member E'. The under edge of the horizontal member has a groove or cut-out e, in which the upper edge of the ridge or flange C may fit, enabling the member E to rest upon such edge and to be held thereby from any perceptible degree of lateral movement. The downward edge of the web E' is formed with an edge e' to rest in groove b, supporting the rail-tread thereon and holding the same substantially from lateral movement. The web is also provided with a shoulder e'', which rests upon a corresponding shoulder b' in the base portion. At regular intervals the ridge or flange C is pierced to receive bolts F, and the web E' is likewise pierced at the same regular intervals, so that the latter may be extended over the base in forming a railroad-bed, and on straight work the parts may be assembled without the necessity of providing other holes for the bolts F. The bolt-holes may be elongated as is necessary to provide for any necessary yielding of the parts.

In Fig. 1 it is shown that the ridge C of the base B may be extended beyond the horizontal member of the base, so as to further provide for the breaking of joints and the rigid connection of the rail structure. It will be understood that the base-ridge C is suitably pierced in such extended portions to register with the holes in the web E' of the rail-tread. The grooves D are located such a distance from the rail-tread that in case of derailment the flange of the wheel will fall into the groove and travel therein without striking the ties and doing any great amount of injury to the rail structure. The grooves are employed on each side of the rail to provide for derailment on either side.

Having described my invention, what I

claim as new, and desire to secure by Letters Patent, is—

- 5 1. A railway construction comprising a base with a vertical ridge and a horizontally-extended member on each side thereof, the said horizontal portion being provided on each side of the ridge with a groove adjacent to the rail-tread to receive the flange of the wheel in case of derailment, substantially as shown. 35
- 10 2. In a rail construction the combination of a base having grooves parallel with the rail-tread to engage the wheel-flange in case of derailment, and a rail-tread having a web to engage the base, the said base and web being 40 pierced for bolts to permit the overlapping of the tread with respect to the base, substantially as shown. 15
- 15 3. In a rail construction, a laterally-extended base portion provided with a vertically-extended web portion, the latter extending beyond the horizontal portion, in combination with a rail-tread adapted to break joint with the horizontal portion of the base and with the vertical portion of the base, substantially 45 as described. 20
- 20 4. In a rail construction, a base extending laterally from the tread-supporting member and provided parallel therewith with a groove on each side thereof to receive the flange of the 50 wheel upon derailment, and a tread member 25 as described. 30

grooved to receive the tread-supporting member of the base and provided with a web to engage a groove in the said base, a groove provided in the said base to receive the web of the tread member, substantially as shown. 35

5. A rail construction comprising a base with a horizontally-extended portion, the latter being provided with a groove to engage the wheel-flange in case of derailment substantially parallel to the rail-tread, substantially as shown. 40

6. A railway construction comprising a ridged base with a horizontally-extended portion provided on each side of the ridge with a groove adjacent thereto to receive the flange of the wheel in the case of derailment, substantially as shown. 45

7. A railway construction comprising a base with a horizontally-extended portion being provided on each side of the center ridge with a groove parallel with the rail-tread to receive the flange of the wheel in case of derailment, substantially as shown. 50

In testimony whereof I affix my signature in presence of two witnesses.

RICHARD M. BURKE.
